(57) **CLAIM**

The ornamental design for a flexible printed wiring board for a module, as shown and described.

DESCRIPTION

FIG. 1 is a front view of a flexible printed wiring board for a module showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a perspective view thereof;

FIG. 8 is an enlarged front view of a portion taken along line 8-8 of FIG. 1;

FIG. 9 is an enlarged rear view of FIG. 8;

FIG. 10 is an enlarged top view of FIG. 8;

FIG. 11 is an enlarged bottom view of FIG. 8;

FIG. 12 is an enlarged right side view of FIG. 8;

FIG. 13 is an enlarged left side view of FIG. 8;

FIG. 14 is an enlarged perspective view of FIG. 8; and,

FIG. 15 is another perspective view thereof, shown in a used condition with a device in broken lines.

The broken lines shown in the drawings represent portions of the flexible printed wiring board for a module that form no part of the claimed design. The dashed-dot-dashed lines indicate a boundary between the claimed and unclaimed portions of the design.
